UNITED STATES PATENT OFFICE.

ADAM KREUTER, OF CHICAGO, ILLINOIS, ASSIGNOR TO AMERICAN LAUNDRY MACHINERY MANUFACTURING COMPANY, OF CHICAGO, ILLINOIS, A CORPORATION OF NEW JERSEY.

IRONING-MACHINE.

No. 926,751.

Specification of Letters Patent.

Patented July 6, 1909.

Application filed December 10, 1906. Serial No. 347,120.

To all whom it may concern:

Be it known that I, ADAM KREUTER, a citizen of the United States, and resident of Chicago, county of Cook, and State of Illinois, have invented certain new and useful Improvements in Ironing-Machines, of which the following is a specification, and which are illustrated in the accompanying drawings, forming a part thereof.

10 The invention relates to ironing machines of that type adapted for ironing the bosom of a garment, and particularly to such machines in which provision is made for shaping the neck-band of the garment and adjacent portion of the bosom.

15 The object of the invention is to provide a laundry machine for finishing shirt bosoms which shall be of simple and improved construction, easily operated, and so formed 20 that the progress of the work may be always in view of the attendant and subject to his control.

25 The invention is exemplified in the structure to be hereinafter described and illustrated in the accompanying drawings, in which—

30 Figure 1 is a side elevation; Fig. 2 is a central vertical section, one position of some of the parts being indicated by dotted lines; Fig. 3 is a front elevation, some of the parts appearing in a vertical cross-section; Figs. 35 4, 5 and 6 are sectional views taken on the lines 4—4, 5—5 and 6—6, respectively, of Figs. 1 and 2; a different position of the parts being shown in Fig. 6 than in Figs. 1 and 2; Fig. 7 is a detail plan view of the 40 ironing table; Fig. 8 is a detail sectional view taken on the line 8—8 of Fig. 1; Fig. 9 is a sectional detail viewed from the line 9—9 of Fig. 6, and Fig. 10 is a detail of Fig. 2 drawn to a larger scale.

45 For the particular form of machine illustrated in the drawings, there is provided a supporting frame comprising upright members 15, 16, and horizontal connecting members 17, 18, 19 and 20. A journal bearing, as 21, 22, is mounted on each of the uprights 15, 16, of the frame of the machine for receiving the trunnions 23, 24, of an ironing 50 roller 25. This roller is preferably adapted to be heated, and as shown is made hollow for receiving a heating fluid which enters through one of the trunnions, as 24, from a steam pipe 26 connected to the end of the 55 trunnion by a packing gland 27.

A table 28 is provided for supporting the articles to be ironed, and is mounted for oscillation beneath the ironing roller 25. As shown this ironing table is of curved form and is carried by a pair of supporting rollers 60 29, 30. A gear-rack 31 extends along the under face of the ironing table for substantially its entire length, and is engaged by a driving gear 32, preferably coaxially mounted with the supporting rollers 29, 30. The 65 movement of the ironing table is guided by a pivoted arm 33, which as shown, comprises two substantially vertical members connected by a cross-member 171 (Fig. 3) and is rotatably connected to the inner end of the 70 table by means of a pin 34 passing through the arm 33 and engaging ears 28^a (Fig. 7) formed integral with the table.

75 Provision is made for raising and lowering the ironing table for the purpose of adjusting the pressure employed in ironing and for moving the ironing table into and out of operative position. To accommodate these movements of the ironing table, the supporting rollers 29, 30, and the driving gear 32 are shiftably mounted, being, as shown, carried by a shaft 35, which is journaled in a vertically oscillatable frame 36, most clearly illustrated in Figs. 2 and 5. The frame 36 is pivotally attached to the 80 body of the machine at 37, 38, and one of its pivots, as 37, is preferably in the form of a shaft for communicating power to the shaft 35, to which the driving gear 32 is fixed by a key 35^a (Fig. 6). The outer end 85 of the frame 36 is carried by a rod 39, rendered adjustable in length by means of a ball nut 40 having a threaded engagement with the upper end of the rod and entering a socket 42 formed in the frame 36. The 90 ball nut 40 carries a pin 43 extending into a groove of the socket for preventing rotation of the nut, and rotation of the rod in the ball nut is normally prevented by means of a lock nut 41. The lower end of the rod 39 100 loosely engages a saddle 44, which, as shown, is carried by a shaft 45 extending transversely of the machine near its base and preferably, also, forms the pivotal support for the guiding arm 33. A spring 46, coiled about the end of the rod 39, reacts between the saddle 44 and a flange 47 formed on the rod to provide a yielding support for the oscillatable frame 36, and a pair of screw-bolts 47^a loosely engage the flange 47 and 105 110

the saddle 44 to limit the movement of the rod 39 in the saddle. Preferably a hand wheel 48 is formed on the rod 39, and the pressure for ironing obtained by means of the spring 46 is readily adjusted by turning the rod in the ball nut 40 after loosening the lock nut 41.

For raising and lowering the ironing table into and out of engagement with the ironing tool, provision is made for vertically shifting the shaft 45, which, as previously described, supports both the saddle 44 and the guiding arm 33. To this end the shaft 45 is carried by links 49, 50 (Fig. 4), rotatably mounted on a shaft 51 extending across the front of the machine and journaled in the upright frame members 15, 16, and a crank shaft 52 is provided for swinging the links. This shaft is preferably journaled at the front of the machine in lugs 53, 54, formed on the horizontal frame member 18, and carries a hand lever 55, having a spring pawl mechanism 56 of ordinary construction and adapted to play over a toothed quadrant 57, which, as shown, is rigidly secured to the frame of the machine at 58 (Fig. 1). The cranks of the shaft 52 are connected to the links 49, 50, at the base of the machine by means of rods 59, 60, and these rods are rendered adjustable in length for the purpose of securing a correct alinement of the parts by means of turn buckles 61.

The ironing table 28 preferably comprises an anvil 62 (Fig. 6) forming the under portion of the table, and an ironing plate 63 having an ironing surface covered with padding 67. Apertured lugs 65, 66, which register when the parts are assembled, are formed on the anvil 62 and on the ironing plate 63, respectively, for receiving a connecting pin 64. The padding 67 is secured in position by a frame 68 fitting over the margins of the plate and pivotally secured thereto adjacent one of its ends, as shown at 69.

The ironing table 28 is preferably provided with a neckband holder 170 for engaging the neck-band of the garment to be ironed, and a cavity 71 is formed in the ironing roller for receiving the neckband holder, the wall of the cavity 71 having, as shown, an overhanging lip 72 (Fig. 9), which co-operates with the rim of the holder to shape the neckband of the garment and adjacent portion of the bosom. Preferably the neckband holder 170 is made sectional and is yieldingly expanded within the neckband of the garment to secure it in place for ironing. As shown it comprises a fixed and a movable section, designated 70 and 73, respectively, the former taking the form of a flange secured to and projecting upwardly from the ironing plate 63, and the latter being carried by rods 74 slidably mounted in lugs 75, 76, formed on the anvil 62. A spring 77, coiled

about each of the rods 74, reacts between one of the lugs 75 of the anvil and a stop 78 carried by the rod about which it is coiled, for normally separating the two parts of the holder. A cross-head 79 connects the rods 74 at their forward ends, and is engaged by a cam stud 79^a carried by the crank arm 80 of a crank shaft 81 journaled in the anvil 62 to advance the rods 74 and the movable section 73 of the neckband holder. The crank shaft 81 is provided with an operating handle 82, conveniently located at one side of the ironing plate. The flange 70 is notched, as indicated at 83, Fig. 9, to receive the shank of a button *x* placed in the front of the neckband *y* of a garment *Z*, and a clip 84, having its outer end bifurcated, as indicated at 85, to straddle the shank of the collar button to secure it in place within the notch, is pivotally attached to the ironing plate 63 within 85 the flange 70 at 86.

A clamp is provided for gripping the skirt of the garment *Z* to stretch it over the ironing board. As shown, this comprises a pair of clamping jaws 87, 88, supported in a transverse position at the outer end of the ironing plate 63 by rods 89, 90, each slidably engaging ears 91, 92, projecting laterally from the anvil 62. A spring 93 is coiled about each of the rods 89, 90, and reacts between one of the ears, as 92 of the anvil, and a stop 94 carried by the rod about which it is coiled to advance the clamping jaws. One of the jaws, as 88, is slidably mounted on the rods 89 and 90, and is yieldingly advanced upon the other jaw 87, which is fixed in position upon the rods, by springs 95, 96, each coiled about one of the rods and reacting between the rear face of the movable clamping jaw and a stop 97, 98, carried by 105 the rod. A cam shaft 99, journaled in the anvil 62 and having an operating handle 100, is provided for shifting the movable jaw 88 to open the clamp. As shown this shaft carries at the end of a crank arm 99^a, a cam 110 roller 101 adapted to engage the downwardly-turned end 102 (Fig. 1) of a link 103, having a sliding engagement with the anvil 62 at 103^a and pivotally connected to the movable jaw of the clamp at 104.

A clamping member 105 is provided for securing the shoulders of the garment *Z* against the margins of the ironing plate 63. As shown, this clamping member is pivotally attached to the anvil 62 at 106 and 107 (Fig. 7), and is provided with gripping jaws 108 and 109 for engaging the margins of the ironing plate at either side of the neckband-engaging flange 70. The clamping member 105 is operated by a crank shaft 110, journaled in the anvil 62 and provided with a crank handle 111 and crank-arm 112. This crank-arm is connected to the clamping member 105 by a pitman 113, which extends through a sleeve 115 formed on the clamp 130

and yieldingly connected thereto by a spring 114 reacting against the outer end 116 of the pitman. A pan 62^a, carried by the anvil 62, surrounds the ironing plate 63 to support 5 the skirt and sleeves of the garment.

Power is applied to the machine for driving the ironing roller 25 and oscillating the ironing table 28, preferably through a belt pulley 117 which, as shown, is loosely mounted 10 on a stub shaft 118 carried by one of the uprights, as 15, of the supporting frame. Idle pulleys 120 and 121, for carrying driving belts, not shown, which run in opposite directions, are mounted, one at either side 15 of the driving pulley 117, and one of them, as 120, turns on the hub of that pulley. A belt shipper 122 plays over the pulleys to shift the belts and control the operation of the machine.

20 Power is transmitted from the driving pulley 117 and a gear pinion 119 formed on its hub beyond the pulley 120, to the ironing roller 25 and the ironing table 28, through a speed-reducing train of gears, including a gear 123 and pinions 124, 128, respectively, mounted on the shaft 37, Fig. 5. A gear 125, rotatably secured to the frame of the machine at 126 (Fig. 1) transmits power from the pinion 124 on the shaft 37 to a gear 127 mounted on the trunnion 23 of the ironing roller 25, and the pinion 128 turns the driving gear 32 of the ironing table mechanism through a gear 129 mounted on the end of the shaft 35.

35 Provision is made for angularly adjusting a gear of the train which operatively connects the ironing table mechanism and the ironing roller, in order that the neckband engaging flange 70 of the ironing table and the cavity 71 of the ironing roller may be caused 40 to accurately register to shape the neckband of a garment. As shown, the gear 127 is adjustably mounted on the trunnion 23, a collar 130 being secured in position on the trunnion 45 by means of a key 131 and having ears 132 and 133 which embrace a lug 134 projecting from the face of the gear 127 and adjustably control its angular position through set-screws 135, 136, each having a threaded engagement with one of the lugs. A set-screw 50 137 pierces the hub of the gear 127 to fix it in any adjusted position.

The belt shipper 122 is controlled by mechanism including a treadle 138, mounted in a 55 conveniently accessible position at the front of the machine upon the end of a shaft 139 journaled in the horizontal frame members 17 and 20. A crank arm 140, Figs. 3 and 4, rises from the treadle shaft 139 at the rear of 60 the machine and is connected by a link 141 to the crank-arm 142 of an upright rock shaft 143 journaled in lugs 144 and 145 projecting from the vertical frame member 15, and a crank-arm 146 (Figs. 1 and 8) formed on the 65 rock shaft 143, is loosely connected (in order

that its movement in the arc of a circle may produce only a rectilinear movement) to a shipper arm 147 leading to the belt shipper 122. Most conveniently the shipper arm 147 extends through the stub-shaft 118, which is 70 made tubular for that purpose.

To start the machine the treadle is depressed by the attendant and a spring is provided for raising the treadle to shift the belts and reverse the direction of movement of the 75 machine whenever the treadle is released by the attendant. Automatic means, acting with sufficient force to raise the treadle in spite of pressure exerted thereon by the attendant, are also provided for reversing the 80 direction of movement of the machine when the ironing table has reached the limit of its backward travel, and the machine is automatically stopped when the ironing table reaches the limit of its forward travel. To 85 raise the treadle 138 whenever it is released by the attendant, a spring 148 (Figs. 3 and 4) reacts between a crank-arm 149, carried by the treadle shaft 139, and a lug 150 projecting from the horizontal frame member 20. 90 To shift the belts when the ironing table reaches the limit of its movement in each direction, a shipper rod 151, operated by the swinging of the table-guiding arm 33, has a sliding engagement with a crank-arm 154, 95 carried by the upright rock shaft 143, and is provided with stops 152 and 153 which engage the crank arm to turn the rock shaft.

As the position of the ironing table 28 is such, near the end of its rearward travel, 100 shown by dotted lines in Fig. 2, that its weight operates to continue the movement of the machine, the shifting of the driving belts from one extreme position to the other to reverse the direction of movement of the machine, is readily effected by so arranging the stop 152 on the shipper rod 151 that it will engage the crank-arm 154 to impart a full stroke to the rock shaft 143.

In order that the machine may be brought 110 to rest at the end of the forward stroke of the table without shock to the parts, provision is made for shifting the driving belts to their mid-position, corresponding to the position of the parts shown in Figs. 4 and 8, before 115 the ironing table reaches the limit of its forward travel and for then permitting the machine to continue its movement in that direction under the momentum of its parts without producing further movement of the belt-shifting mechanism. To this end the stop 120 153 is disposed upon the shipper rod 151 to engage the crank-arm 154 of the rock shaft 143 before the ironing table reaches the limit of its forward stroke. The shipper rod 125 151 is yieldingly connected by a spring 157 to the table-guiding arm 33, and carries a stop 166 which prevents the rod traveling forward farther than is required to turn the rock shaft 143 to its mid position. The stop 130

166 is adapted to engage a fixed part of the machine, as the horizontal frame member 20. A pin 155 carried by the arm 33 moves in a slot 156 formed at the end of the shipper rod 5 151, and is provided at its outer end with a disk 158 for preventing the lateral displacement of the rod on the pin. The spring 157 reacts between the disk 158 and an adjusting screw 159 carried by a collar 159^a mounted 10 on the rod.

The forward movement of the ironing table is limited by the engagement of the guiding arm 33 with the table-supporting rollers 29 and 30, and preferably a brake is 15 provided for retarding the movement of the parts when the ironing table approaches the end of its forward travel to avoid shock when these parts come into contact. As shown this brake takes the form of a band 160, 20 Figs. 1 and 5, surrounding a pulley 160^a mounted on the shaft 35, and has one end rigidly secured to the oscillatable frame 36 at 161 and the other attached to the lower end of a lever 162 pivotally secured to the frame 25 36 at 163, and having its longer end projecting into the path of a stud 164 carried by the ironing table. A buffer 165, carried by the horizontal frame member 20, is engaged by the guiding arm 33 when the ironing table 30 28 reaches the limit of its rearward movement.

In using the device the garment to be ironed is secured to the ironing table 63 preferably by means of the clamps already described, and has its neckband *y* surrounding the neckband holder 170 and its bosom spread upon the face of the ironing board in front of the holder. The machine is then set in motion by depressing the treadle 138, the 40 ironing table traveling backward beneath the ironing roller 25 (the neckband holder 170 intermeshing with the cavity 71 of the roller) until the limit of its backward movement is reached, or until the treadle 138 is released by the attendant. The driving belts are then shifted upon the pulleys 117 120 and 121 to cause the ironing table and the ironing roller to travel in the opposite direction, if at the limit of backward movement of the table, by reason of the engagement of the stop 50 152 with the crank-arm 154 of the rock shaft 143, or if because of the release of the treadle by the attendant before the limit of backward movement of the table is reached, by 55 reason of the turning of the treadle shaft 139 and rock shaft 143 by the spring 148. The direction of movement of the ironing table may be reversed at any time during its forward travel by depressing the treadle 138, but if permitted to complete its forward 60 stroke, the machine will then be brought to rest by the engagement of the stop 153 of the shipper rod 151 with the crank-arm 154 of the belt shipping mechanism. As the driving belts are thrown to the proper position to

drive the machine in one direction when the treadle 138 is depressed and in the opposite direction when the treadle is raised, this treadle may be operated to cause a continued oscillation of the ironing tool over any part 70 of the garment, such a movement comprising a full stroke of the machine in each direction being effected, as shown, by depressing the treadle at the end of each forward stroke of the ironing table and holding it down until 75 the following rearward stroke has been completed. The work may be smoothed upon the board by the hands of the attendant, as it advances to the ironing tool, and if for any reason the ironing does not progress satisfactorily, the ironing tool and ironing table may be instantly disengaged by shifting the lever 55 to lower the table and the parts permitted to return to the position of starting.

The overhanging lip 72 at the walls of the 85 cavity 71 formed in the ironing roller 25 may be accurately shaped to fit the neckband-engaging flange 70 of the ironing table, and the parts may be adjusted to cause this cavity and the flange to properly register by adjusting the angular position of the gear 127 on the trunnion 23 of the ironing roller, this being easily effected, as shown, by turning the set-screws 135, 136, of the collar 130. Preferably the gears connecting the ironing roller 90 25 and the ironing table 28 with the drying pulley 117 are so proportioned that the surface speed of the ironing roller and the ironing table are substantially the same. For this reason there is no sliding of the ironing 100 tool over the garment, and a so-called domestic finish is produced. If desired, however, these gears may be so related in size that the ironing roller will be driven at a greater or less speed than that at which the table moves, 105 and a sliding of the ironing tool over the garment will be thereby effected and a polished surface produced.

I claim as my invention—

1. In an ironing machine, in combination, 110 an ironing board having a neckband-engaging flange, and an ironing roller coöperating with the board and having a cavity for receiving the flange.

2. In an ironing machine, in combination, 115 a driving shaft, an oscillatable ironing board having a neckband-engaging flange, an ironing roller coöperating with the board and having a cavity for receiving the flange, and gear connection between the driving shaft 120 and the roller and between the driving shaft and the board.

3. In an ironing machine, in combination, 125 a curved faced ironing board having a neckband engaging flange, and an ironing roller coöperating with the board and having a cavity for receiving the flange.

4. In an ironing machine, in combination, 130 a driving shaft, an oscillatable ironing board having a neckband-engaging flange, an iron-

ing roller coöperating with the board and having a cavity for receiving the flange, and gear connection between the driving shaft and the roller and between the driving shaft 5 and the board, one of the gears being angularly adjustable.

5. In an ironing machine, in combination, an ironing board having a neckband-engaging flange, an ironing roller coöperating with 10 the board and having a cavity for receiving the flange, and an angularly adjustable gear for driving the roller.

6. In an ironing machine, in combination, an ironing tool, a frame yieldingly supported 15 beneath the tool, a roller and a gear journaled in the frame, means for driving the gear, a curved faced ironing table carried by the roller and coöperating with the ironing tool, a gear-rack formed on the under face of 20 the table for engaging the gear and an arm for guiding the movement of the table.

7. In an ironing machine, in combination, an ironing tool, a pivotally mounted frame, a spring for yieldingly advancing the free end 25 of the frame toward the ironing tool, a pressure roller and a gear coaxially mounted in the free end of the frame, a driving shaft coaxial with the pivot of the frame and carrying a pinion operatively engaging the gear, 30 an ironing table carried by the pressure roller and coöperating with the ironing tool, and a rack formed on the under face of the ironing table and engaging a gear mounted on the shaft of the roller.

35 8. In an ironing machine, in combination, an ironing tool, a shiftable support, a pressure roller carried thereby, a curved faced oscillatable ironing table carried by the roller and coöperating with the ironing tool, and an 40 arm for guiding the movement of the table pivotally attached to the shiftable support.

9. In an ironing machine, in combination, an ironing tool, a pressure roller, a shiftable support, a spring reacting between the support, 45 and the pressure roller, a curved faced oscillatable ironing table carried by the pressure roller and coöperating with the ironing tool, and a guiding arm pivotally attached to the shiftable support and to the table.

50 10. In an ironing machine, in combination, an ironing tool, a frame pivotally attached to a fixed support to swing toward and away from the ironing tool, a pressure roller journaled in the frame, a shiftable sup-

port for the free end of the frame, a curved 55 faced oscillatable ironing table carried by the roller and coöperating with the ironing tool, and an arm for guiding the movement of the table pivotally attached to the shiftable support.

11. In an ironing machine, in combination, an ironing tool, a frame pivotally attached to a fixed support to swing toward and away from the ironing tool, a pressure roller journaled in the frame, a shiftable 60 support, a spring reacting between the free end of the frame and the shiftable support, a curved faced oscillatable ironing table carried by the pressure roller and coöperating with the ironing tool, and a guiding arm pivotally attached to the shiftable support and to the ironing table.

12. In an ironing machine, in combination, an ironing tool, a shiftable support, a pressure roller carried thereby, a curved 75 faced oscillatable ironing table carried by the roller and coöperating with the ironing tool, an arm for guiding the movement of the table pivotally attached to the shiftable support, a crank shaft for shifting the support, a 80 hand lever carried by the shaft, and ratchet and pawl mechanism for securing the hand lever in an adjusted position.

13. In an ironing machine, in combination, an ironing tool, a pressure roller, a 85 shiftable support, a spring reacting between the support and the pressure roller, means for adjusting the tension of the spring, a curved faced oscillatable ironing table carried by the pressure roller and coöperating 90 with the ironing tool, a guiding arm pivotally attached to the shiftable support and to the table, a crank shaft for shifting the support, a hand lever carried by the shaft, and ratchet and pawl mechanism for securing the 95 hand lever in an adjusted position.

14. In an ironing machine, an ironing roller provided with a recess and an ironing table having a collar band to register with said recess, in combination with means for 100 maintaining the registration and for simultaneously rotating said roller and reciprocating said table, as and for the purpose described.

ADAM KREUTER.
